UNITED STATES PATENT OFFICE

2,411,810

AUDIO REACTOR

Morris Sander, Philadelphia, Pa., assignor to
 Radio Corporation of America, a corporation of
 Delaware

Application September 20, 1943, Serial No. 503,054

7 Claims. (Cl. 171—242)

1

My present invention relates to a reactor for use at audio frequencies, the inductance of which it is desired to vary over a predetermined range. In practice it has been found difficult to obtain adequate inductance change in high Q, low-frequency inductors. In one application of the present invention, operating at about 930 cycles per second, I have been able to obtain an inductance variation of $\pm 15\%$, the Q of the coil being between 30 and 35.

In accordance with the invention, the reactor is made adjustable and comprises a coil form of insulating material having a central and two end compartments which are open-ended, in alignment and disposed in parallel relation. A coil of wire is wound around the coil form in a direction transverse to the direction of the compartments, and a fixed laminated iron core having an air gap is positioned within each of the end compartments. There is further provided within the central compartment a powdered-iron core which is capable of adjustment relative to the coil and air-gaps of the fixed cores for the purpose of varying the inductance of the reactor.

The novel features characteristic of my invention are set forth with particularity in the appended claims. The invention itself, however, both as to its construction and mode of operation together with the objects and advantages thereof, will best be understood by reference to the following description taken in connection with the accompanying drawing in which

Fig. 1 is a plan view to scale of the reactor assembly in accordance with the invention;

Fig. 2 is a front elevational view of Fig. 1;

Fig. 3 is a view in cross-section taken along the line 3—3 in Fig. 1, showing the two-part fixed laminated core;

Fig. 4 is a cross-section taken along the line 4—4 in Fig. 1;

Fig. 5 shows the complete assembly of the reactor enclosed in a casing;

Fig. 6 is a detail view of the core adjusting means, and

Fig. 7 represents the schematic circuit of the reactor.

Referring to Fig. 1 the reactor comprises an inductance winding or coil 1 which is wound, in a plane parallel to the surface of the drawing, around a centrally located spool or coil form 2. The coil leads are indicated at 3 and 4. The spool 2 may be of moulded nylon or other suitable insulating material and is provided with a central compartment 5, square-shaped in cross-section, and two similar end compartments 6 and

7 which are rectangular in cross-section. The three compartments are open-ended at the top and bottom, are aligned with one another, and disposed in parallel relation. The central compartment which is extended somewhat above and below the two end compartments, as shown more clearly in Fig. 4, is adapted to receive an iron core 8 made of compressed iron dust, the core being slidably adjustable within the compartment 5 by means to be hereinafter described.

The two end compartments 6, 7 are each adapted to receive the center leg 9, 9' of a composite fixed core 10 constituted by stacks of laminations which may be of Numetal (a nickel alloy) or other suitable material. For convenience of assembly the fixed laminated core 10 is made of two similar parts 11 and 11' which are paired, as shown more clearly in Fig. 3, to provide the center leg 9, 9', the portions of which are adapted to be inserted into an end compartment from opposite sides and to be positioned in fixed spaced relation to provide an air gap 10' between them.

In order to maintain the pair of laminated cores 10 in fixed parallel relation and also to rigidly retain in position the two parts 11, 11' of each core there is provided at each end a clamping plate 12 to which a pair of brackets 13 are spot welded or otherwise attached. The two brackets of each clamping plate are properly spaced and are adapted to embrace the corresponding sides of the two fixed cores 10, and by means of four screws 14 the oppositely disposed clamping plates 12 are held together. Each plate is provided with a flange or foot portion 15 for convenience of attachment by means of screws, rivets or otherwise to a base plate 16 (Fig. 5).

The base plate 16 has attached to it a pair of terminals 17, 17 to which the leads 3, 4 from the inductance coil 1 are connected. A suitable rectangular-shaped metal can housing 18 is fitted over the entire assembly and is soldered or otherwise connected to an upturned flange 19 of the base plate 16. The can housing is provided at its two shorter sides with a pair of flanges or foot portions 20 for attachment to a chassis or other mounting, and is further provided in its upper wall with an opening through which there is passed a screw shaft 21 which is adapted to slidably adjust the iron core 8 within the center compartment 5 of the coil form 2.

The iron dust core 8 is also square-like in cross-section and is provided with a centrally located bore 22 which extends for about three-quarters of the length of the core from the bottom. The remaining portion of the core above the bore is

internally threaded and is adapted to ride on the screw shaft. Frictionally within the bore and positioned near the lower end thereof is a nut plate or retaining member 23 through which the screw shaft is also threaded. A compression spring 24 is concentrically arranged around the shaft within the bore and extends between the nut plate and the opposing internal rim portion of the core in order to take up any play or back lash between the core and the screw shaft.

In order that the adjustable core may be accurately centered within its compartment there is utilized a block member or plug 25 formed with an aperture 26 within which the lower end of the screw shaft is adapted to be seated. The centering block is suitably attached by screws, rivets, or the like, to the cover plate 16, is similarly shaped in cross-section as the center compartment, and is of sufficient length to extend into said compartment at the lower end and to 20 be snugly fitted therein.

In order that the core may be adjustably set from the outside of the can housing, the latter is provided in its top wall with an aperture 18 through which there extends an externally 25 threaded bushing 21, the intermediate portion of which is provided with a first disc member 38 and a second larger disc member 30'. The two disc members may form an integral part of the bushing, or otherwise mounted thereon, as by means 30 of a forced fit. The larger disc 30' is concentrically arranged with respect to the housing aperture 18' and is soldered to the top wall of the housing. By means of a washer 28 and a locknut 29, the bushing and its associated parts are 35 clamped in position. The bushing is adapted to receive within its bore the upper unthreaded end of the screw shaft 21 which is retained therein and confined only to rotary motion by means of a C washer 31 engaging a circumferential groove 32 in the shaft. A washer 33 and a spring washer 34 are interposed between the C washer and the bushing in order to lock the shaft against vertical movement. For effecting the desired adjustment of the core, rotation of the screw shaft by 40 means of a suitable tool, such as a screw driver, will cause the core to ride up or down depending upon the direction of shaft rotation. An internally tapped cap 35 may be provided to fit over the exposed end of the bushing on which the screw head is seated to prevent tampering after an adjustment has been made.

In one embodiment of the invention the coil consisted of 1,000 turns of wire, the air gap in each fixed core was $\frac{1}{32}$ ", and the adjustable core was 1" in length and .594" square. With the adjustable core all the way in (Fig. 5) and a source of voltage at the input terminals of the reactor of 1 volt and a frequency of 1,000 cycles, the inductance was approximately 0.47 henry, whereas with the core all the way out, the inductance was approximately 0.36 henry, an inductance change of approximately 30%, or $\pm 15\%$ from a mean core adjustment giving 0.415 henry. The inductance change is due to the fact that the powdered iron dust core varies the inductance not only by acting on the turns of the coil but also by short circuiting the air gaps of the fixed core stacks.

In contradistinction to the usual reactor assemblies employed in radio apparatus, the inductance and the Q of the reactor of the present invention are not affected by the can housing for the reason that the fixed laminated cores act

as a magnetic shield to confine the magnetic flux between them.

While I have shown and described a preferred embodiment of my invention, it will be understood that various modifications and changes will occur to those skilled in the art without departing from the spirit and scope of this invention. I therefore contemplate by the appended claims to cover any such modifications as fall within the true spirit and scope of my invention.

What I claim is:

1. A reactor comprising a coil form of insulating material having a central and two end compartments, said compartments being open-ended, in alignment and disposed in parallel relation, a coil of wire wound around the coil form in a direction transverse to the direction of the compartments, a fixed laminated iron core extending into each of the end compartments, and an adjustable powdered-iron core extending into the central compartment.

2. A variable reactor for audio frequencies comprising a coil form of insulating material having a central and two end compartments which are disposed in parallel relation, a coil wound around the coil form in a direction transverse to the direction of the compartments, a fixed iron core extending into each of the end compartments, said fixed cores each having an air gap located in the field of the coil, and a powdered-iron core adjustably movable within the central compartment for varying the inductance of the reactor.

3. A variable reactor for audio frequencies comprising a coil form of insulating material having a central and two end compartments, said compartments being open-ended, in alignment and disposed in parallel relation, a coil of wire wound around the coil form in a direction transverse to the direction of the compartments, a fixed laminated iron core provided with an air gap extending into each of the end compartments, and an adjustable powdered-iron core movable within the central compartment capable of varying the inductance of the reactor.

4. A variable reactor in accordance with the invention defined in claim 3 wherein the reactor is housed within a container provided with an aperture which is aligned with the central compartment and through which there is adapted to 50 extend the means for adjusting the powdered-iron core.

5. A reactor comprising a coil form of insulating material having a central and two end compartments said compartments being open-ended, in alignment and disposed in parallel relation, a coil of wire wound around the coil form in a direction transverse to the direction of the compartments, a pair of three-limbed laminated iron cores having their respective central limbs extending into one of the end compartments and their outer limbs positioned externally of the coil, and an adjustable powdered-iron core extending into the central compartment.

6. A variable reactor for audio frequencies comprising a coil form of insulating material having a central and two end compartments which are disposed in parallel relation, a coil wound around the coil form in a direction transverse to the direction of the compartments, a pair of three-limbed iron cores having their respective central limbs extending into one of the end compartments and their outer limbs positioned externally of the coil, each of said cores constituting 70 a closed magnetic circuit except for an air gap in the central limb located in the field of the coil,

and a powdered-iron core adjustably movable within the central compartment relatively to the coil and air gaps for varying the inductance of the reactor.

7. A variable reactor for audio frequencies comprising a coil form of insulating material having a central and two end compartments, said compartments being open-ended, in alignment and disposed in parallel relation, a coil of wire wound around the coil form in a direction transverse to 10

the direction of the compartments, a pair of laminated iron cores disposed in parallel planes, each provided with a central limb located in one of the end compartments, each of said cores constituting a closed magnetic circuit except for an air gap in each core, and an adjustable powdered-iron core movable within the central compartment relatively to the coil and air gaps for varying the inductance of the reactor.

MORRIS SANDER.
